UNITED STATES PATENT OFFICE.

JAMES P. KARR AND JOHN D. RAUCH, OF LOGANSPORT, INDIANA.

BARGE.

No. 874,849.

Specification of Letters Patent.

Patented Dec. 24, 1907.

Application filed February 12, 1907. Serial No. 357,012.

To all whom it may concern:

Be it known that we, JAMES P. KARR and JOHN D. RAUCH, citizens of the United States, and residents of Logansport, in the county 5 of Cass and State of Indiana, have invented an Improvement in Barges, of which the following is a specification.

Our invention is an improvement in the hulls of barges, boats or floats, particularly 10 such as are used to furnish a flat and stable deck or platform for attachment and support of apparatus employed for operating steam shovels or diggers in land or marine excavations. It is a matter of the utmost import- 15 tance that such barges shall be constructed in the most rigid manner, without unduly increasing the cost. Our improvement at- 20 tains these objects, and the details of construction, arrangement and combination of parts are as hereinafter described and shown 25 in the accompanying drawings, in which

Figure 1 is a plan view of the frame or body of a barge or boat, the deck or platform being removed. Fig. 2 is a longitudinal 25 vertical section of a portion of the hull. Fig. 3 is a transverse vertical section on the line 3—3 of Fig. 1. Fig. 4 is a face view of a side portion of the hull showing the longitudinal planking separated in groups or divi- 30 sions. Fig. 5 is a plan view of the parts shown in Fig. 4. Fig. 6 is a side view of the barge complete, save that a portion of the deck facing is cut away. Fig. 7 is a per- 35 spective view of one of the divisions or sec- tions composing the bottom of the barge.

The body of the barge is oblong and rectangular. The vertical sides A are formed of a series of groups of side planking 1, whose meeting ends 1^a are scarfed or cut upon an 40 incline as shown in Figs. 2, 4, 6, the same being fitted close together and the ends of the points thus formed being cut vertically so as to form abutting shoulders at 2, see Figs. 2 and 4. Screw bolts 3 pass vertically 45 through the side planking 1 and top and bottom ribs or beams 6 and 8; and, as shown in Fig. 2, other bolts 3^a pass through the scarfed and meeting ends 1^a of the side planking, thus connecting them firmly but 50 detachably. Additional bolts 4 pass vertically through the side planking, at points intermediate the top beams 6, thus further securing them together. Parallel to the sides of the barge we arrange interiorly two 55 bulkheads B which are spaced from each

other about the same distance that they are spaced from the sides A, see Figs. 1 and 3.

Deck planking 7 is nailed to the cross beams 6. The bottom of the hull is formed in sections C, see Fig. 7, each section comprising side planking 1^b having notches or mortises in their under sides and cross beams 8 connecting such planking and projecting through the mortises. These parts are se- 60 cured together by the bolts 3 as before stated. Planking 9 is nailed to the under side of the beams 8 and the bolts 3 pass through portions of the same as shown in Fig. 2. The sections C are arranged end to end, two beams 8 being thus adjacent and in 65 contact as shown in Fig. 2, and the ends of the side planking 1^b abutting as shown in Fig. 2. One of such beams is secured by a short bolt 10 to the side plank which is pro- 70 vided with mortises. Thus, both the sides 75 and bottom of the hull are constructed in separable sections which obviously offers a great advantage when it is required to construct the barge at a place distant from that at which it is to be launched. All the parts 80 composing the hull may be separated from each other and transported in that condition, or if conditions warrant, each hull section may be made up and transported entire. 85 As shown in Fig. 6 the hull is made prac- tically in three longitudinal sections, but of course any other desired number may be employed.

For the purpose of applying stress to the hull lengthwise and thus holding the several 90 sections of the same in rigid alignment, we arrange tie rods 11, see Figs. 1 and 2, di- 95 rectly above the bottom bars or ribs 8 and extending from end to end of the barge, clevises being provided at the ends for ad- justment of tension. As indicated in Fig. 1 the clevises are connected with the corner posts 12, which are bolted to both the sides and ends of the barge. We also provide a 100 truss consisting of iron or steel rods 13 which extend from one end portion of the barge to the other and over beams 14 arranged on the deck, as will be well understood without detailed description.

By the above described construction, ar- 105 rangement and combination of parts we form a barge which is comparatively light and inexpensive, yet has great rigidity and durability.

It will be understood that calking is requi- 110

site to form tight joints between the side and end planks and the bottom covering as well as between the lower ribs 8 and the side planking in which they are mortised.

5. What we claim is—

1. The improved barge comprising a frame formed in sections consisting of side planks whose ends are scarfed and fitted together, longitudinal bulkheads extending from end to end, transverse deck beams secured to the side planks and intervening bulkheads, and bottom beams arranged transversely and extending through mortises in the lower side planks, vertical bolts 10 passing through the parts named and binding them together and longitudinal straining rods and truss rods arranged, substantially as described.
2. An improved barge composed of longitudinal sections which are detachably connected, the meeting ends of the side planks being jointed together, top and bottom beams and ribs arranged transversely and planking applied to form the deck and the 15

bottom of the hull and screw bolts passing 25 vertically through the top and bottom beams and ribs, substantially as described.

3. The improved barge constructed in longitudinal sections adapted to be separated and each comprising side planks whose ends 30 are scarfed and fitted together; bolts passing vertically through the meeting scarfed ends and thus connecting the said sections; top beams arranged transversely; bottom-covering sections comprising planking, transverse 35 ribs which are fitted in mortises in the lowest side planks, screw-bolts passing through the side planking and the top and bottom beams or ribs; and straining rods arranged longitudinally of the barge and passing over supports 40 at the center of the same and extending to the bottom and end portions of the barge, as shown and described.

JAMES P. KARR.
